US00D567243S

(12) **United States Design Patent** (10) **Patent No.:** **US D567,243 S**
Ashida et al. (45) **Date of Patent:** **** Apr. 22, 2008**

(54) **CONTROLLER FOR ELECTRONIC GAME MACHINE**

(75) Inventors: **Kenichiro Ashida**, Kyoto (JP); **Masato Ibuki**, Kyoto (JP); **Shinji Yamamoto**, Kyoto (JP); **Hirokazu Matsui**, Kyoto (JP); **Akiko Suga**, Kyoto (JP)

(73) Assignee: **Nintendo Co., Ltd.**, Kyoto (JP)

(**) Term: **14 Years**

(21) Appl. No.: **29/287,574**

(22) Filed: **Aug. 24, 2007**

Related U.S. Application Data

(62) Division of application No. 29/253,817, filed on Feb. 14, 2006, now Pat. No. Des. 556,760.
